(57) **CLAIM**

The ornamental design for a coffee maker as shown and described.

DESCRIPTION

FIG. 1 is a front perspective view of a coffee maker showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a front perspective view thereof in a condition of use with a cup and carafe; and,

FIG. 9 is a front perspective view thereof in a condition of use with two different cups.

The broken lines illustrate portions of the coffee maker or environment thereof that form no part of the claimed design.
